OR D 16,628

DESIGN.

C. O. SCHWARTZ.

OIL STOVE.

No. 16,628.

Patented Apr. 13, 1886

UNITED STATES PATENT OFFICE.

CHARLES O. SCHWARTZ, OF MILWAUKEE, WISCONSIN.

DESIGN FOR AN OIL-STOVE.

SPECIFICATION forming part of Design No. 16,628, dated April 13, 1886.

Application filed October 24, 1885. Serial No. 180,785. Term of patent 7 years.

To all whom it may concern:

Be it known that I, CHARLES O. SCHWARTZ, a citizen of the United States, residing at Milwaukee, in the county of Milwaukee and State 5 of Wisconsin, have invented and produced a new and original Design for Oil-Stoves, of which the following is a specification, reference being had therein to the accompanying photograph, which is a perspective view illustrating the design of my said oil-stove.

The legs of the stove are four in number, as shown at *a a*, and represent two curved strips united at their converging centers, and with a general inclination at an angle of about forty-five degrees. Above the legs is the flat open-work base *b*, of general rectangular oblong shape. Above this rise the sides *C*, of ornamental open scroll-work, consisting of the central oval medallion, *c*, surrounded by the oval frame *c'*, the center of whose sides curves inward to meet the sides of the medallion *c*, and are connected above and below said point of union to ornamental uprights *c''*, which also connect with the upper corner-pieces, *c' c'*, and the larger and wider corner-pieces *c' c'* of the side frame, *C*, the sides being further ornamented by various scrolls and curved lines, as shown at *c' c'*, *c' c'*, and *c'*. The hearth *D* of the stove is nearly rectangular in form, and 30 its three side edges have an ornamental polished band, *d*, as shown, and on a plane above said hearth is the stove proper, *E*, having at its base and top similar ornamental polished edge bands, *e* and *e'*, and upright corner panels, *F F*, &c., ornamented as shown, and a similar upright ornamental panel, *F'*, centrally divides the front of the stove, leaving two sections with arched openings *f f* on each side, and above which are ornamental designs, as shown.

40 The characteristic features of my design are as follows: first, the side frames of ornamental open scroll-work, consisting of a central medallion surrounded by an oval frame, the center of whose sides curves inward to meet the

sides of the medallion, with ornamental uprights, corner-pieces, and curved lines, all united and blended together; second, the stove-body having ornamental base and top polished edge strips, corner ornamental panels, front upright central ornamental panel, and ornamental sections on each side of the front panel, with arched openings; and, third, the design as a whole.

Having thus described and illustrated my new and original design, what I claim, and desire to secure by Letters Patent, is—

1. In a design for oil-stoves, the side frames, *C*, of ornamental open scroll-work, consisting of the central medallion, *c*, surrounded by the oval frame *c'*, the center of whose sides curves inward to meet the sides of the medallion, the ornamental uprights *c'' c''*, the corner-pieces *c' c'*, and the scrolls and curved lines *c' c' c'*, all united and blended together, as shown and set forth.

2. In a design for oil-stoves, the stove-body *E*, with ornamental base and top polished edge strips, *e e'*, corner ornamental upright panels, *F F*, front upright central ornamental panel, *F'*, and ornamental sections on each side of the front panel, *F'*, with arched openings *f f*, as shown and set forth.

3. The design for oil-stoves hereinbefore described, consisting of the inclined ornamental legs *a a*, flat ornamental open-work rectangular oblong base *b*, ornamental open scroll-work side frames, *C C*, hearth *D*, with ornamental polished edge band *d*, and stove-body *E*, with ornamental polished edge strips *e e'*, upright panels *F F F'*, and ornamental front sections with arched openings *f*, all substantially as shown and set forth.

In testimony whereof I affix my signature in presence of two witnesses.

CHARLES O. SCHWARTZ.
